US00D799542S

(12) **United States Design Patent** (10) **Patent No.:** **US D799,542 S**
(45) **Date of Patent:** **** Oct. 10, 2017**

(54) **DISPLAY SCREEN OR PORTION THEREOF WITH ICON FOR PRESENTATION OF ANALYTE DATA**

(71) Applicant: **Dexcom, Inc.**, San Diego, CA (US)

(72) Inventors: **Esteban Cabrera, Jr.**, San Diego, CA (US); **Katherine Yerre Koehler**, San Diego, CA (US); **Brian Christopher Smith**, San Marcos, CA (US); **Eric Cohen**, San Diego, CA (US); **Rian Draeger**, San Diego, CA (US); **Paul Kramer**, Austin, TX (US); **Paul Noble-Campbell**, Austin, TX (US); **Eli Reihman**, San Diego, CA (US); **Leif Bowman**, San Diego, CA (US)

(73) Assignee: **Dexcom, Inc.**, San Diego, CA (US)

(**) Term: **15 Years**

(21) Appl. No.: **29/583,284**

(22) Filed: **Nov. 3, 2016**

Related U.S. Application Data

(62) Division of application No. 29/509,286, filed on Nov. 14, 2014, now Pat. No. Des. 773,529.

(57) **CLAIM**

The ornamental design for a display screen or portion thereof with icon for presentation of analyte data, as shown and described.

DESCRIPTION

The patent or application file contains at least one drawing executed in color. Copies of this patent or patent application publication with color drawings will be provided by the Office upon request and payment of the necessary fee.

The FIGURE shows a front view of a display screen or portion thereof with icon for presentation of analyte data that incorporates the new, original, and ornamental design.

The broken lines in the drawings illustrate a display screen or portion thereof and form no part of the claimed design.
